COMBINATION SEPARABLE CRIB FRAME
AND CHEST OF DRAWERS STRUCTUREFrancis H. Weigle, Chicago, and Bernard Yuffy,
Oak Park, Ill.

Application April 9, 1948, Serial No. 20,124

2 Claims. (Cl. 5-2)

1

This invention relates to a combination crib and chest of drawers structure and is more particularly adapted to such a structure embodied in an infant's crib combined with a chifforobe.

In an important aspect the invention contemplates a reversible or invertible combination of child's crib and chifforobe in which the crib portion may be uppermost, for use as such, with the chifforobe portion below and providing a support for the crib portion, or, alternatively, in which the chifforobe portion may be uppermost and the crib portion below, in which latter use the crib portion provides not only a support for the chifforobe portion but also a storage compartment.

In still another aspect, the crib portion and chifforobe portion may be separately used, the crib portion for example as a child's play pen, and the chifforobe portion separately as such, or as a desk.

The invention desirably includes a separable base portion upon which may be immediately supported either the crib portion or the chifforobe portion as preferred.

One important object of the invention is that when the structure is used as a crib, the latter is desirably elevated to a position which avoids the necessity of stooping by a person attending a child using the crib, a side of the crib advantageously having a swinging gate member giving access to crib portion without interference thereby with unimpeded access to the chifforobe portion beneath the crib.

The invention aims to provide a structure of this class which may be economically manufactured in quantity production and which has a minimum number of parts consistent with its objects, and which may be readily assembled and disassembled by the user.

These and other objects and advantages will be apparent from the following description, taken with the accompanying drawings, of an illustrative embodiment of the invention, and in which drawings—

Figure 1 is a perspective view showing the present invention used as a crib with chifforobe below;

Figure 2 is a perspective view showing an alternative assembly in which the chifforobe is above and the crib portion below serving as storage space;

Figure 3 is a so-called exploded view of the parts in diagrammatic pre-assembly relation to provide the combination shown in Figure 1;

Figure 4 is a plan view of the assembly of Fig-

2

ure 1 showing opening movement of gates for the crib;

Figure 5 is an enlarged sectional detailed view of a tenon arrangement for interlocking the parts;

Figure 6 is a similar view showing a complementary mortise arrangement;

Figure 7 shows a modified gate lock construction;

Figure 8 is a fragmentary elevational view of the gates of Figure 7 in locked position; and

Figure 9 is a perspective view of the chifforobe portion with doors removed leaving an open storage compartment, in which arrangement the portion may function as a desk.

Referring in detail to the illustrative construction shown in the drawings, the numeral 11 indicates a base upon which rests a chest of drawers or storage portion 12 upon which again is supported a bed or crib portion 13.

As shown in Fig. 1, the parts just referred to, which, as indicated in Fig. 3, are separable, may be assembled first with the storage portion immediately on the base 11 and then the bed portion 13 above and supported by the storage portion 12.

In this instance, the base 11 is of rectangular frame-like formation of dimensions suitable to receive the lower edges of the storage portion 12 thereon spaced slightly inwardly of the outer edge of the base.

The storage portion 12 as here shown comprises storage drawers such as 14, 15, 16 and 17, at one side, and a storage compartment 18 (Fig. 9) at the other side, which may be closed by the outwardly swinging doors 19 and 20.

The bed portion 13, as here illustrated, is in the form of an infant's crib having having the mattress supporting surface 21, which may be of flat panel-like formation and may have the solid panel-like head and foot members 22 and 23, a back 24 of the so-called rail fence type, and a gate element along its front represented in this instance by the two outwardly swinging gates 25 and 26, also of the so-called rail-fence type. The gates 25 and 26 may swing on hinge rods 27 and 28 respectively (Fig. 4) and may be provided with locking members of the so-called bolt type 29 and 30.

For keying the parts 11, 12 and 13 together one of the parts may have a pin or tenon 31 (Fig. 5) vertically extending therefrom and the other adjacent part a pin well or mortise 32 (Fig. 6).

In the modification shown in Figs. 7 and 8, the gates 32 and 33 may pivot on hinge rods 34

and 35 and one of these gates as gate 32 may have vertical sliding movement with respect to its hinge rod 34. Thus when the companion gate 33 is moved into its closed position the gate 32 may then be so moved and lifted on its hinge rod 34 as to permit a locking tongue 36, which is rigid with the gate 32, to drop into a slot 37 in the upper edge of the gate 33 to maintain the gates in locked position.

In the modification shown in Fig. 9 the storage portion 12 may have the doors 19 and 20 removed leaving the storage space 18 open at which time the portion 12 may function as a desk, the space 18 providing a knee-hole. For this purpose the portion 12 has a flat panel-like top 12a.

In the assembly shown in Fig. 1, with the crib portion 13 uppermost, the person attending the infant occupying the crib is not required to stoop to reach the infant, since the crib portion is elevated by the storage portion 12 to a height somewhat comparable to that of the usual household table-top. At the same time since access to the crib is afforded by the outwardly swinging gates 25 and 26 it is unnecessary for the person to reach over the top of the crib side. When the gates 25 and 26 are locked together, by suitable means such as hereinbefore indicated, the infant is prevented from falling out of the crib, the sides being also high enough to prevent its climbing over. At the same time, access is afforded to the drawers 14, 15, 16 or 17 and the storage compartment 18 without moving the bed portion or crib.

After the child reaches an age where it would no longer use the crib, the structure may be advantageously made use of entirely for storage purposes in which case the assembly may be reversed or inverted as shown in Fig. 2, with, in this case, the crib portion 13 directly on the base 11 and the storage portion 12 thereabove and supported thereby. Since the gates 25 and 26 open outwardly the crib portion may be used for storage purposes, with the drawers 14, 15, 16 and 17 and the storage compartment 18 thereabove at the height of the customary chifforobe.

If it be desired to use the portion 12 as a desk, as indicated in Fig. 9, the doors 19 and 20 having been removed, the crib portion 13 may be used separately as a child's play pen.

The crib gates may have handles 38, the doors 19 and 20 handles 39, and the drawers handles 40.

So constructed and arranged, we have disclosed a novel and useful article of household furniture which has particular utility at the present time with the high prices of furniture and the paucity of space commonly available for living purposes. An infant usually requires both a crib and a chifforobe and these pieces of furniture separately require double the amount of floor space which is necessitated by the structure here disclosed. At the same time, the usual crib is low and requires a person attending the child to stoop or bend over frequently, which may be eliminated by the present invention. Commonly, if a play pen be provided as the child gets older, a third article of furniture must ordinarily be added, whereas, as here shown, the crib portion may be arranged to serve additionally as a play pen. Again as the child grows older, commonly the crib must be discarded, whereas with

the present construction it may be utilized to provide a storage space with a chifforobe above.

Manifestly the invention is not intended to be limited to details of construction shown for purposes of exemplification. Furthermore, it is not essential that all features of the invention be used conjointly as various combinations or sub-combinations may at times be advantageously employed. Such changes may be made in various modifications of the invention as fall within the scope of the appended claims without departing therefrom.

The invention having been described, what is here claimed is:

15. 1. In a combination separable crib and chest of drawers structure, a base element, a crib frame supported on the base element, tenons on the lower face of the crib frame, mortises in the upper face of the base element receiving the tenons, one side of said frame comprising laterally opening gates, a chest of drawers supported on the crib frame, tenons on the lower face of the chest of drawers, mortises in the upper face of the crib frame receiving the tenons on the chest of drawers, said tenons and mortises being respectively corresponding and interchangeable on the base element and crib frame and on the crib frame and chest of drawers whereby the base element may support the crib frame directly and the chest of drawers indirectly through the intermediation of the crib frame, or the chest of drawers directly and the crib frame indirectly through the intermediation of the chest of drawers, said gates being openable and closable in either arrangement for access to the interior of the crib frame.

2. In a combination separable crib and chest of drawers structure, a base element, a crib frame supported on the base element, interengaging means at the lower end of the crib frame and corresponding interengaging means at the upper face of the base element, a chest of drawers supported on the crib frame, interengaging means at the lower end of the chest of drawers and corresponding interengaging means at the upper face of the crib frame, said interengaging means and corresponding interengaging means being respectively identical and interchangeable whereby the chest of drawers may support the crib frame on the base element, or the crib frame may support the chest of drawers on the base element, or either one singly may be supported on the base element, and said means may be selectively operative.

FRANCIS H. WEIGLE,
BERNARD YUFFY.
